UNITED STATES PATENT OFFICE.

MALCOLM GORDON, OF LISBURN, IRELAND.

YARN WINDING, TWISTING, AND DOUBLING MACHINE.

1,164,343.

Specification of Letters Patent. Patented Dec. 14, 1915.

Application filed November 19, 1914. Serial No. 872,998.

To all whom it may concern:

Be it known that I, MALCOLM GORDON, a citizen of the United States of America, residing at Lisburn, county Antrim, Ireland, have invented certain new and useful Improvements in and Relating to Yarn Winding, Twisting, and Doubling Machines, of which the following is a specification.

This invention has reference to automatic stop motions of the detector box type for use in connection with yarn winding, twisting and doubling machinery, and relates more particularly to an auxiliary attachment forming a combined yarn clearer and slub or lump detector which is adapted to be supplied to, and act in conjunction with, stop motions of this type, for the purpose of increasing the utility thereof.

Heretofore stop motions have been caused to act by the breaking or running out of the yarn.

Under the present invention the attachment forming the slub or lump detector is so constructed and arranged that when, during the onward travel of the yarn, a lump, or slub, or knot, contacts with a movable part thereof it will cause that part to be moved and so operate means as to cause the stop motion to come into action automatically and stop the travel of the yarn without breaking same, whereupon the worker or attendant may remove the slub or lump.

The movable part or detector proper is suitably supported and is adapted to be moved against the action of a pendulum, weight, spring, or like means, and the passage for the yarn through or past the same is such that, while the movement of the detector stops the machine, it also releases the slub or lump without breaking the yarn, so that there is a considerable saving resulting from the avoidance of waste yarn.

In order that my invention may be clearly understood I have hereunto appended explanatory sheets of drawings whereon it is shown in some of its forms by way of example or illustration.

Figures 1 and 2 are respectively elevation and plan views of a slub detector in accordance with my invention as applied to a

winding frame fitted with an ordinary stop motion of the box detector type, and Fig. 3 is a front view of the oscillating detector plate showing the tapered openings there-in. Figs. 4 and 4^a are views showing another or modified form of oscillating detector plate and means for adjusting same. Figs. 5 and 6 are respectively elevation and plan views of a slub detector in accordance with my invention as applied to a twisting frame having a stop motion of the box detector type.

On the drawings the same reference letters wherever repeated indicate the same or similar parts.

Referring to the drawings:—In carrying out my invention as applied to a doubling frame and as shown at Figs. 1 to 3, I provide in addition to the usual detector drop pins *a*, one or more additional drop pins. In the example shown an additional drop pin *b* is provided. The extra drop pin *b* is suspended by a cord *b*¹ having one end *b*² suitably supported at *b*³, its other end *b*⁴ being attached to the detector plate *d* at *b*⁵ (see also Fig. 3.) The detector plate *d* is supported by and swings about a pivot *d*¹ and it is normally held vertical by the action of the suspended weight or pendulum *d*² which also puts sufficient tension on the cord *b*¹ to keep it normally taut, but on the detector or plate *d* being struck by a slub or knot in the yarn it can be freely oscillated thereby so that the cord *b*¹ is slackened and the pin *b* drops into engagement with the stop motion ratchet *e* thereby bringing the ordinary stop motion into action. When struck by a slub or knot as above described the detector plate *d* is immediately oscillated and at the same time its oscillation allows the slub or knot to pass onward without breaking the yarn and as the stop motion is immediately brought into action the operator can then remove the slub or knot and re-start the machine. As shown in Fig. 3 the detector plate *d* may be made with upwardly tapering slots or slits for different "counts" of yarn and thicknesses of slubs or lumps to be cleared. Instead of using a detector plate *d* with suspended weight *d*¹ as shown in Figs. 1 to 3, I may,

if desired, use a slitless plate f (see Fig. 4) suspended below the pendulum f^1 on the pivot f^2 , the plate f etc. being suspended over and adjustably supported with respect 5 to a plate or bar g , the yarn passing between the upper surface of the bar g and the lower edge of the plate f and so that any predetermined size of lump or knot will oscillate the plate f and cause it to operate the stop 10 motion in the manner hereinbefore described while the lump passes on and clears the detector plate f without breaking the yarn.

In Figs. 1 and 2 there is an additional drop pin c suspended by a cord h having its 15 one end h^1 attached to a fixed support h^2 while its other end passes through an eye h^3 and is secured to one arm i^1 of a bell crank lever i , the other arm i^2 of which has an adjustable finger or projection i^3 . On 20 the completion of the winding of a cop or bobbin a bar l suitably pivoted, is moved to a position to engage with and move the finger i^3 and consequently lever i so that the cord h is slackened and the pin c caused to 25 actuate the stop motion.

Figs. 5 and 6 show an example of my attachment as applied to a twisting frame in which the stop motion is also actuated on the breaking of the yarn by providing an 30 additional drop pin m suspended by a cord n which is supported at its one end n^1 on a fixed support n^2 while its other end is secured to an arm o^1 of a bell crank lever o whose other arm o^2 is adapted to be acted 35 on by the end p^1 of a weighted lever p on the roller axis g . The other end p^2 of the lever p has an eye p^3 through which the yarn passes and, in the event of its breaking, the end p^2 of the lever falls thereby raising 40 the end p^1 which moves the lever o so that the cord n is slackened, and the pin m then engages and actuates the stop motion. The lever o normally tensions the cord n so as to keep the pin m clear of the stop motion.

45 In certain cases the yarn may, after passing the detector above described, be guided by a porcelain guide or the like s and thence through an eye i (see Fig. 1).

The distinctive improvement of the lump 50 stop motion attachment as described is that the onward travel of the yarn is stopped without the yarn being broken whereas with the old type of stationary detectors, when the slub or lump struck the detector the 55 yarn was generally broken at the weakest spot with the result that a considerable portion of yarn had to be pulled back entailing delay and also more waste than necessary in cutting out the lump.

60 Having now fully described my invention what I claim and desire to secure by Letters Patent is:—

1. In conjunction with the stop motion of a yarn winding, twisting or doubling ma-

chine, a detector plate capable of being oscillated by an increase in the size of the 65 yarn, a fixed support, a cord connected to said plate and to said support, and a drop pin suspended by the cord and lowered to operate the stop motion when the plate is 70 moved and the cord slackened.

2. In conjunction with the stop motion of a yarn winding, twisting or doubling machine, a detector plate having openings 75 therein for the passage of the yarn and capable of being oscillated by an increase in the size thereof, a fixed support, a cord connected to said plate and to said support, and a drop pin suspended by the cord and lowered to operate the stop motion when 80 the plate is moved and the cord slackened.

3. In conjunction with the stop motion of a yarn winding, twisting or doubling machine, a detector plate having upwardly tapering openings therein for the passage of 85 the yarn and capable of being oscillated by an increase in the size thereof, a fixed support, a cord connected to said plate and to said support, and a drop pin suspended by the cord and lowered to operate the stop motion when 90 the plate is moved and the cord slackened.

4. In conjunction with the stop motion of a yarn winding, twisting or doubling machine, a detector plate capable of being 95 oscillated by an increase in the size of the yarn, means whereby the plate is normally held against movement, a fixed support, a cord connected to said plate and to said support, and a drop pin suspended by the 100 cord and lowered to operate the stop motion when the plate is moved and the cord slackened.

5. In conjunction with the stop motion of a yarn winding, twisting or doubling machine, a detector plate capable of being oscillated by an increase in the size of the 105 yarn, a weight secured to the lower part of the plate whereby it is normally held vertical, a fixed support, a cord connected to 110 said plate and to said support, and a drop pin suspended by the cord and lowered to operate the stop motion when the plate is moved and the cord slackened.

6. In conjunction with the stop motion 115 of a yarn winding, twisting or doubling machine, a detector plate capable of being oscillated by an increase in the size of the yarn, a pendulum secured to the lower part 120 of the plate whereby it is normally held vertical, a fixed support, a cord connected to said plate and to said support, and a drop pin suspended by the cord and lowered to operate the stop motion when the plate is moved and the cord slackened.

7. In conjunction with the stop motion of a yarn winding, twisting or doubling machine, a detector plate capable of being os-

cillated by the yarn, a fixed support, a cord attached to the detector plate and to the support, and a drop pin suspended by the cord whereby when the detector plate is os-
5 cillated the cord is slackened and the pin lowered thereby operating the stop motion.

In testimony whereof I affix my signature in presence of two witnesses.

MALCOLM GORDON.
